UNITED STATES PATENT OFFICE.

HUBERT C. HART, OF UNIONVILLE, CONNECTICUT, ASSIGNOR TO THE H. C. HART MANUFACTURING COMPANY, OF UNIONVILLE, CONNECTICUT, A CORPORATION OF CONNECTICUT.

ARTICLE OF CUTLERY.

1,161,665.

Specification of Letters Patent.

Patented Nov. 23, 1915.

Application filed March 27, 1915. Serial No. 17,382.

To all whom it may concern:

Be it known that I, HUBERT C. HART, a citizen of the United States, residing at Unionville, in the county of Hartford and State of Connecticut, have invented certain new and useful Improvements in Articles of Cutlery, of which the following is a specification.

This invention relates to an article of cutlery.

As may be inferred, the invention is capable of general use; that is to say the article of cutlery may be a knife, a fork, a spoon or analogous article of tableware.

The object of the invention is to provide a device of the character set forth which is simple in construction, susceptible of inexpensive manufacture and which although it has a hollow handle is provided with means of an effective nature for preventing the entrance of water into said handle.

In the drawings accompanying and forming part of the present specification I have shown one of the several convenient forms of embodiment of the invention which to enable those skilled in the art to practise the same will be set forth fully in the following description. I do not restrict myself to this disclosure; I may depart therefrom in several respects within the scope of the invention defined by the claims following said description.

In said drawings the invention is shown embodied in a knife, although as will be inferred from what I have already noted, I do not limit myself in this particular.

Referring to the drawings: Figure 1 is a side elevation of a knife involving the invention. Fig. 2 is a side elevation of the handle of said knife. Fig. 3 is a view of the handle as seen from the left in Fig. 2 with the sides of the handle separated. Fig. 4 is a developed view of the handle blank. Fig. 5 is an elevation of the blade. Fig. 6 is a top plan view, and Fig. 7 is a side elevation of a filling. Figs. 8 and 9 are cross sections on the lines 8-8 and 9-9 respectively of Fig. 1.

Like characters refer to like parts throughout the several views.

There are knives and similar implements comprising a hollow handle and a blade, the tang or shank of the blade being fitted in the handle. It is a fact that when these knives and similar tools are put into dish

water, the water passes into the handle around the openings between the tang and the shank of the blade and the handle. This water will remain in the handle and at times passes therefrom while the user of the knife or analogous article is eating a meal, which condition is a disagreeable one. I provide means whereby the passage of water into the hollow handle of a knife or equivalent piece of cutlery is effectually and positively precluded so that I get all the advantages of a hollow handle, such as lightness, ease of manufacture and strength without the objectionable feature to which I have alluded.

Referring to the drawings, the numeral 2 denotes a suitable handle and 3 a suitable blade member. The term "blade member" as will be obvious, is used in a generic sense to include not only a knife blade but equivalent articles such as fork or spoon members, two merely of several illustrations. The handle 2 which is of novel construction may be made from a blank such as that shown in developed form in Fig. 4, said blank comprising duplicate sections 4 integrally connected and foldable toward each other along the longitudinally extending line 5. The two sections or sides 4 of the handle are longitudinally grooved or channeled and when their free edges are brought into abutment as shown in Figs. 8 and 9 a hollow handle will be the result, the handle being closed at its rear and open at its front, the front opening being adapted to receive the tang or shank 6 of the blade 7, the tang or shank being gripped or clamped by and between the sides of the hollow handle 2. In practice the butt joint between the free edges of said sides is almost imperceptible and the said sides can be so closely brought together that they will firmly hold the blade 7 in position and against accidental displacement. The foregoing is a somewhat brief description of an article of cutlery in which my invention can be desirably incorporated.

The hollow handle 2 is preferably wholly filled by a suitable filling means preferably of compressible material, so that when the handle blank is closed upon the blade this compressible filling of whatever nature it may be can be further densified so as not only to immovably hold it in position but to insure the adequate and complete filling of the interior of the handle. As will be evident, the filling means may vary, although

the one-piece filler 8 answers satisfactorily in this connection. I can with advantage make this filler 8 of cork, thus insuring lightness and at the same time obtain compressibility. Generally speaking the filler 8 is of a shape agreeing with the form of the interior of the hollow handle 2; although the filler initially is a trifle larger than said interior. To insure further compressibility of 10 the filler 8 the latter may have as shown the kerfs or notches 9 and 10 extending inwardly from opposite ends thereof. In addition to the function mentioned the kerf 10 acts to receive the tang or shank 6 of the 15 blade 7.

The parts may be assembled as follows: Initially the sides 4 of the handle 2 will be bent toward each other along the line 5 and brought to a condition approximately similar to that illustrated in Fig. 3. The filler 20 8 will then be crowded into the space between the sides 4 through the opening at the top thereof. The tang or shank 6 will then be inserted into the kerf or slit 10 after 25 which the handle 2 will be closed by bringing the free marginal portions of the sides 4 thereof into firm substantial abutment with each other. This results in compacting the filler 8, the handle 2 when closed wholly 30 inclosing the filler which is exteriorly invisible. The filler preferably has an interlocked connection with the blade 7. To secure this result the shank or tang 6 may have an opening or perforation as 11 therein into which the substance of the filler 8 will be forced when the handle 2 is closed to thereby anchor the filler and the blade together.

It will be clear that the folding together 40 of the side portions 4 of the handle in the manner already described produces a butt

joint. It will be obvious that the filling is co-extensive with this joint, so that the filling effectually prevents the entrance of moisture into the hollow handle by way of said 45 joint or seam.

What I claim is:

1. A hollow handle comprising longitudinally abutting side portions and a compressible filling in the handle, the filling being 50 coextensive with the joint between said side portions and being initially cross sectionally of greater extent than the cross sectional extent of the interior of the handle, said portions when abutting acting compressively 55 against the filling and the filling preventing the entrance of water into the handle by way of said joint, combined with a blade, the handle having an end opening, the blade having a shank extending through said 60 opening into the handle, the filling also closing the end opening of the handle.

2. A hollow handle comprising side portions integrally connected and longitudinally abutting, and a compressible filling in the handle, the filling being coextensive with the joint between said portions and being initially cross sectionally of greater extent than the cross sectional extent of the interior of the handle, said portions when abutting 65 acting compressively against the filling, combined with a blade having a shank extending into the handle, the filling having a kerf 70 to receive the shank, whereby the filling will grip the shank when the handle compresses 75 the filling.

In testimony whereof I affix my signature in presence of two witnesses.

HUBERT C. HART.
